UNITED STATES PATENT OFFICE.

ELMER J. SNOW, OF MAHWAH, NEW JERSEY, ASSIGNOR TO AMERICAN BRAKE SHOE & FOUNDRY COMPANY, OF JERSEY CITY, NEW JERSEY, A CORPORATION OF NEW JERSEY.

MACHINE FOR FORMING BRAKE-SHOES.

No. 832,633.

Specification of Letters Patent.

Patented Oct. 9, 1906.

Application filed February 17, 1905. Serial No. 246,005.

To all whom it may concern:

Be it known that I, ELMER J. SNOW, a citizen of the United States, and a resident of Mahwah, in the county of Bergen and State of New Jersey, have made and invented certain new and useful Improvements in Machines for Forming Brake-Shoes, of which the following is a specification.

My invention relates to an improvement in machines for forming brake-shoes, and more particularly to a machine for punching the hole in the steel or malleable metal back of a "steel-back shoe" after the back has been molded in the body of the shoe.

The object of the invention is to provide a device of this character which shall be simple in construction and which will easily, readily, and effectively perform its functions.

With these and other ends in view the invention consists in certain novel features of construction and combinations of parts, as will be hereinafter fully described, and pointed out in the claims.

In the accompanying drawings, Figure 1 is a view in perspective of my improved device. Fig. 2 is a horizontal sectional view thereof, taken on the line 2-2 of Fig. 3. Fig. 3 is a view, partly in side elevation and partly in section, the several parts being shown in their adjustments prior to the punching of the hole in the steel back. Fig. 4 is a sectional view showing the pin for holding the punch in its raised position. Fig. 5 is a sectional view showing the several parts in their positions after the formation of the opening in the steel back. Fig. 6 is a detached view of the pneumatic barrel forming part of the spring mechanism.

Referring to the drawings, 7 represents the base or stand, of an inverted-box-like form, consisting of the side plates 8, front plate 9, rear or back plate 10, and top 11, preferably cast in one piece and with the flange 12. To the top 11 is bolted or otherwise secured the bracket 13, having located thereon the guide-block 14, provided with a central opening through the same for the passage of the punch 15, the latter at one end being provided with the head or knob 16 and at its lower end with a cutting edge. In this guide-block is secured the pin 17, surrounded by the coil-spring 18, the tendency of which latter is to keep the inner end of the pin in frictional contact with the punch 15 in order

to hold the latter in its several different relative positions.

From the under side of the top plate 11 depends the well or receptacle 19, out of which leads the passage-way 20 and with which connects an opening 21, formed in said top plate. Into said latter opening 21 is fitted the die-block 22, having a central passage or opening 23 extending through the same, the upper cutting edge of which, in conjunction with the lower cutting edge of the punch 15, is adapted to form the hole or opening in the steel back, as hereinafter described, the disk punched from the back falling or dropping through the opening in the die-block into the well or receptacle 19 and down the inclined bottom plate 24, Fig. 5, and out of the machine.

To the front plate 9 of the base or stand is bolted or otherwise secured the bracket 25, provided with the slot 26, in which is adjustably secured the support 27, the latter being adapted to be raised or lowered by being turned or rotated in the clamping-nuts 28.

In practice one end of the shoe 29, Fig. 3, consisting of the cast body 30, having cast in or on the upper face or surface thereof the steel or malleable metal back 31, is placed upon the support 27, the latter being first vertically adjusted to the proper height and also longitudinally adjusted in the bracket 25 toward, or away from the stand 7 in accordance with the length of the shoe under formation, the opposite end being placed or supported on the die-block 22 and in such position that the cored opening 32 will fall directly below and in line with the punch 15. The punch is then lowered until its cutting end rests on the back 31 of the shoe, as illustrated in Fig. 3. By means of a hammer, mallet, or other proper tool 33, Fig. 1, a blow is given to the punch, whereby a circular hole or opening is cut in said back 31, the disk of metal (not shown) cut from the back falling out of the machine, as hereinbefore described.

In order to "strip" the machine—that is, return the parts to their normal positions, so that the finished shoe may be removed and another inserted in its place—I secure to the four brackets or flanges 34, formed on or secured to the inner sides or surfaces of the box or stand 7, the cylinder or barrel 35, containing the piston 36, the latter being provided with the piston-rod 37, extending upwardly

through an opening formed in the top 38 of the barrel or cylinder 35 and encircled by the coiled spring 39, one end of the latter impinging against the top 38 and the opposite end against the piston 36, the tendency of said spring being to keep the piston in its lowered position, as illustrated in Fig. 5.

Into the lower end of the barrel or cylinder 35 leads an air-inlet pipe 40, connected to any suitable source of air-pressure, said pipe being provided with a three-way cock 41, operated or controlled by the lever 42, the latter being held in its normal adjustment by the spring 43. After the hole has been punched in the steel back and the parts assume the several positions as illustrated in Fig. 5 a pull on the lever 42 will allow the air under pressure to pass through the pipe 40 and into the cylinder 35 below the piston 36, forcing the latter, with its piston-rod 37, upwardly until said piston-rod striking the lower end of the punch 15 will carry the latter upwardly to its normal position, as indicated in Fig. 1. Upon releasing the lever 42 it will be returned to its normal position by the spring 43, thereby so turning the cock 41 as to allow the air under pressure in the cylinder to escape. Thereupon the spring 39, which has been compressed by the upward stroke of the piston, will return the latter to its lowered position. (Illustrated in Fig. 5.)

As the tendency of the piston-rod in lifting or forcing the punch out of the opening in the steel back is to lift the shoe off of the die-block 22, I provide a clamping mechanism to hold said shoe in place during this part of the operation, this clamping mechanism consisting of horizontal bar or rod 44 the ends of which are secured to the vertical posts 45, around which are coiled the springs 46, the upper ends bearing against said rod 44 and the lower ends against the top plate 11 of the stand. These rods 45 pass down through openings formed in the upper plate 11 of the stand and have their lower ends linked to the arms 47, keyed to the shaft 48, mounted in the sides 8 of the stand. To one end of this shaft 48 is secured the lever 49, the free end being provided with a step 50, whereby to operate the same by foot power. In the operation of the machine and just prior to turning on the air-pressure for "stripping" the operator depresses the lever 49, thereby lowering the rod or bar 44 onto the shoe, as illustrated in Fig. 5, thereby securely holding or clamping the shoe onto the die-block. The several parts are held in these positions until after the punch has been raised to its normal position, as hereinbefore described, whereupon the lever 49 being released the springs 46 will raise the bar 44 to its normal position, and thereby so release the shoe that it may be removed from the machine and another one inserted in its place.

65 To recapitulate, the shoe is placed in posi-

tion in the machine, the punch struck by the mallet 33, the lever 49 lowered to clamp the shoe in place, and the air-pressure turned on. Finally, the lever 49 is released and the shoe removed.

70 From the foregoing description it will be seen that the machine is simple and cheap to construct and can be easily, readily, and effectively operated even by an unskilled workman.

75 Having fully described my invention, what I claim as new, and desire to secure by Letters Patent, is—

1. In a machine of the character described, the combination with a stand, and a punch supported thereby, of means connected with said stand for holding one end of the shoe, a support for holding the opposite end of the shoe, said support being adjustable in a plane parallel with the movement of the punch, and means for raising the punch to its normal position, substantially as described.

80 2. A machine of the character described having in combination a stand, a punch supported thereby, a spring-actuated clamping mechanism for holding one end of the shoe, a bracket fixed to the stand, a support for the opposite end of the shoe, said support being adjustable in the bracket toward and from the said clamping mechanism, and being also 85 adjustable in a plane parallel with the movement of the punch, means for holding the punch in its adjustments, and mechanism for raising said punch to its normal position, substantially as described.

90 3. In a machine of the character described, the combination with a stand, of a punch supported on said stand, spring-actuated mechanism for holding one end of the shoe, a lever for operating said mechanism, an adjustable support for the opposite end of the shoe, and means contained within said stand and engaging with said punch for raising the latter to its normal position, substantially as 95 described.

100 4. In a machine of the character described, the combination with a stand, of a punch supported by said stand, spring-actuated means for holding said punch in its several positions, a spring-actuated bar for holding 105 one end of said shoe, a lever for operating said bar, an adjustable support for the opposite end of the shoe, and pneumatically-operated mechanism contained within said stand and engaging the lower end of said punch for 110 raising the latter to its normal position, substantially as described.

115 Signed at New York, borough of Manhattan, in the county of New York and State of New York, this 15th day of February, A. D. 120 125 1905.

ELMER J. SNOW.
